CLAIM

The ornamental design for a product dispenser, as shown and described.

DESCRIPTION

FIG. 1 is a perspective view of a product dispenser, showing my new design;

FIG. 2 is a front view thereof;

FIG. 3 is a rear view thereof;

FIG. 4 is a right side view thereof;

FIG. 5 is a left side view thereof;

FIG. 6 is a top view thereof, wherein the bottom view is identical image of this view;

FIG. 7 is a perspective view of a second embodiment of the product dispenser;

FIG. 8 is a front view thereof;

FIG. 9 is a rear view thereof;

FIG. 10 is a right side view thereof;

FIG. 11 is a left side view thereof; and,

FIG. 12 is a perspective view of a third embodiment of the product dispenser with the only difference being all the triangular elements along the side are shown in full lines. The broken lines showing is for illustrative purposes only and forms no part of the claimed design.
